By Chas. H. Burleigh

UNITED STATES PATENT OFFICE.

S. EMERSON HARTHAN, OF WORCESTER, MASSACHUSETTS.

MACHINERY FOR PROPELLING AND STEERING BOATS.

SPECIFICATION forming part of Letters Patent No. 366,662, dated July 19, 1887.

Application filed November 26, 1886. Serial No. 219,893. (No model.)

To all whom it may concern:

Be it known that I, S. EMERSON HARTHAN, a citizen of the United States, residing at Worcester, in the county of Worcester and 5 State of Massachusetts, have invented certain new and useful Improvements in Machinery for Propelling and Steering Boats, of which the following, together with the accompanying drawings, is a specification sufficiently full, 10 clear, and exact to enable persons skilled in the art to which this invention appertains to make and use the same.

The objects of my present invention are, first, to provide an engine and propelling apparatus for boats, which apparatus can be 15 connected to and disconnected from the boat for temporary use at pleasure, and which is light and portable and can be applied to row-boats of ordinary construction without defacing or making change in the construction of the boat; second, to provide an auxiliary stern-post carrying an engine, propeller, and 20 steering mechanism, disposed and operating as hereinafter described, and having means for its detachable connection with the stern 25 of the boat; third, to provide a tubular steering-rudder adapted to serve as a condenser for the propelling-engine of a boat or other vessel, in combination with a pumping mechanism for removing the water of condensation 30 from the interior of said rudder; fourth, to provide, in combination with the propeller, condenser, and engine, a simple and efficient pumping apparatus and feed-water heater, 35 as hereinafter described, for returning the water of condensation; fifth, to provide convenient facilities for storage of fuel, and to render the apparatus complete in its efficiency and simple and compact in its construction 40 and form. These objects I attain by mechanism the nature and operation of which is illustrated in the drawings, and hereinafter explained.

The several features of my invention will 45 be understood from the following description, the particular subject-matter claimed being hereinafter definitely specified.

In the drawings, Figure 1 is a side view of a portable engine and propeller apparatus, 50 illustrating the features of my invention. Fig. 2 is a rear view of the same. Fig. 3 is a ver-

tical section through the engine, valves, condenser, and pumping devices.

In referring to parts, A denotes a frame or auxiliary stern-post adapted to occupy a position against the stern of the boat B (illustrated by dotted lines) in line with the keel, and provided with facilities whereby it can be attached to and detached from the boat in a ready and convenient manner.

C indicates a screw-propeller mounted to revolve on a stud or axis fixed at the lower part of said frame A, and provided with inclined wings of ordinary form.

D indicates the engine cylinder or motor 65 mounted on the upper end of the frame, the piston-rod D' of said engine being connected direct by the pitman D² with a crank or wrist pin fixed to the propeller-wheel, as indicated at e. The reciprocating cross-head d of the 70 engine works in guides d' on the frame A.

The engine-valve E is made substantially as indicated in Fig. 3, and is arranged to reciprocate in the valve-box E', into which steam is admitted above and below the valve-slides. 75 Said valve is operated by the rod e, connected with the wrist-pin at e, which is furnished with a crank, as indicated. The reciprocation of the valve mechanism also, in the present instance, serves to operate the condenser-pump 80 devices which are connected therewith.

F indicates a steering-rudder constructed to serve as a condenser for the engine. Said rudder preferably consists of a series of pipes disposed closely adjacent to each other in a flat 85 coil and connected with a tubular standard, F', which is pivoted and supported upon a backwardly-extending arm, A', at the lower end of the frame A.

The tube E², which carries the engine-valve, 90 serves as the exhaust-pipe, and extends downward within the tubular standard F' to near the bottom thereof, where it is provided with a valve, i. Within said tube E², and connected therewith at its upper and lower ends, is a 95 tube or pipe, G, of smaller diameter, which extends up through the engine-valve and valve-box cap into a packing-coupling, J, by which the feed-supply pipe of the boiler or generator is connected thereto. The tube E² is perforated between the valve-slides, as at n, so that the exhaust-steam from the cylinder can pass 100

into and down said tube, around the pipe G, and is also perforated to allow steam to pass out into the top pipe, f, of the rudder-coil F. The lower pipe, f', of the rudder-coil connects 5 with the interior of the tubular standard, and the passage is provided with a valve, I, which serves, in connection with the valve i, as a condenser-pump, as the tubes E² and G are reciprocated by the action of the rod e. Suitable packing or stuffing boxes are provided for the tubes at m, m', and m², as indicated.

The water condensed from the steam in the rudder-coil is, by the reciprocating action of the tubes, pumped up through the inner tube, 15 G, and returned into the boiler M. Said tube serves also as a feed-water heater, by its being surrounded by exhaust-steam within the tube E².

The tubular standard F' is provided with a 20 suitable tiller or yoke, H, fixed to its upper end, to which steering-ropes are to be connected for swinging the rudder to one side or the other when steering the boat.

For attaching the engine-supporting frame 25 or auxiliary stern-post A to the boat, I employ a detachable clamping device, which device is preferably constructed as shown in Fig. 1, and consists of a screw-threaded clamp, K, having an arm, K', through which a set-screw, 30 K², is arranged. Said arm K' is arranged to hook over the stern of the boat B, and is secured by turning down the screw K², thus drawing the frame A against the stern of the boat with sufficient force to return it in position. Adjustment for different thickness of 35 timber in the boat is afforded by screwing the clamp K more or less into the frame.

Ears l, having holes for bolts, are formed on the frame A, and, if preferred, said frame can 40 be attached to the boat by bolts or screws instead of the clamp K. This latter method of fastening may be deemed preferable, except in cases where it is not desired in any way to deface or make holes in the stern of the boat.

The frame A is preferably formed hollow, 45 as at a, and the internal cavity utilized as a receptacle for liquid fuel for use in generating the steam or vapor, or for running the engine, proper connection being made for withdrawing said fuel from the cavity by means of a wick or a pipe extending into the cavity.

The engine, propeller, and steering devices, arranged as herein shown, are compact, light, and portable, and can be put onto or taken off 55 from an ordinary row-boat at pleasure, so that a single apparatus will serve for different boats, to be used when required. The mechanism in a size suitable for an ordinary row-boat is sufficiently light to be carried by a man 60 without inconvenience, and can be readily fixed in position for use upon the boat. Larger sizes of the apparatus may be made for use on canal-boats or other vessels, when desired.

By constructing the rudder as a condenser 65 and arranging the reciprocating tube E² as the exhaust-pipe for the engine and as a rod for operating the steam-valves and pump-valves,

and with the feed-tube disposed within said exhaust-pipe, I am enabled to produce a very light and simple condensing-engine, capable 70 of giving high efficiency of vacuum, while the same is in compact, convenient, and desirable form for portability and use, in the connection and for the purposes specified.

In the present instance I have illustrated a 75 vertically-reciprocating engine to be operated by steam or expansive vapor; but it will be understood that an explosive-gas engine or hydrocarbon-engine or a rotary steam-engine could be employed for use in connection with 80 the auxiliary stern-post or hollow detachable frame A of the form shown in accordance with my invention, and I desire to include such as within the scope of my claim.

It will be further understood that the feature of my invention, comprising the steering-rudder constructed to serve as a condenser, and provided with pumping mechanism for removing the water from the interior thereof, may be employed in connection with an engine 90 of other style from the one herein illustrated—as, for instance, with a rotary engine or with an engine disposed in horizontal or other position; also, that said rudder, instead of being formed of a series of pipes, may be made of 95 plates and partitions disposed for inclosing an interior space, into which the steam or vapor is delivered, the said space communicating with the exhaust and pump tubes in substantially the same manner as does the coil shown. 100

I am aware that boat-propelling apparatus has been heretofore described and patented, 105 wherein a supporting-frame carrying a propeller, a steering-rudder, and crank devices for operating the propeller by hand is adapted for temporary and detachable connection with the stern of a boat. I do not therefore herein make claim, broadly, to a detachable propelling mechanism; but such patented mechanism is, so far as appears, differently constructed 110 and adapted to be operated by different means from that herein illustrated and described.

I am also aware that in a previous patent a condenser has been shown placed within the supporting-frame of a ship's propeller. Such 115 construction, however, is not similar to my steering-rudder, as it does not include pumping mechanism or means combined therewith for removing the water of condensation from the interior of the rudder.

What I claim as of my invention, and desire to secure by Letters Patent, is—

1. A portable propelling apparatus for boats, consisting of the auxiliary stern-post frame adapted to be temporarily and detachably secured in stationary position to the stern of the boat and provided with a steam-motor engine, and a screw propeller-wheel mounted upon said frame with operating connections, substantially as and for the purpose set forth. 125

2. The combination of a steam-motor engine and a screw propeller-wheel operated by said engine, mounted upon a portable auxiliary stern-post provided with attaching devices,

whereby it can be detachably connected in stationary position on the stern of the boat, and a steering-rudder mounted to swing on said auxiliary stern-post, substantially as and for the purpose set forth.

3. The detachable stationary auxiliary stern-post A, having the backwardly-extended arm A', axis-stud, and cross-head guides a', combined with the propeller-wheel C, the laterally-swinging steering-rudder pivoted to said arm, and the motor-engine mounted on the upper end of said post, substantially as shown and described.

4. The combination, with a boat, of the auxiliary stern-post A, having guides a', and a backwardly-projecting axis stud near its lower end, the propeller-wheel C, mounted to rotate on said stud and provided with a crank, e, the engine cylinder D, and valve-box E, mounted on the upper end of said post, and the operating-rods D² and e, connecting the propeller-crank with the engine-piston and valve mechanism, and means, substantially as described, for attaching said post to the stern of the boat and supporting the same with the propeller-stud at stationary position axially in line therewith.

5. A steering-rudder constructed with an interior space or passage adapted to serve as a condenser and provided with a tubular standard, in combination with a pumping mechanism for removing the water of condensation, substantially as set forth.

6. The combination, with a boat, of a detachable auxiliary stern-post, a screw propeller-wheel and a driving-engine mounted on said post, a tubular steering-rudder connected with the exhaust-ports of said engine, and a pumping mechanism for removing the water of condensation from the interior of said rudder, substantially as set forth.

7. The steering-rudder constructed with an interior space or passage to serve as a condenser, provided with a double hollow tubular standard, in combination with a propeller-wheel disposed in front of said standard, an engine, a supporting-frame having the bearing-arm A', for supporting the foot of said standard, means for supporting the top of the in-

ner standard-tube, and the yoke H, for shifting the rudder, substantially as and for the purpose set forth.

8. The combination, with the engine and the steering-rudder adapted to serve as a condenser, of a pump disposed within the rudder-standard for drawing the water of condensation from within the rudder, substantially as set forth.

9. The combination of the engine, the combined rudder and condenser having an upright tubular standard, the reciprocating tube arranged within said standard and provided at one end with the engine-valve E and at the other end with the pump-valve i, and the water-delivery pipe G, arranged through said tube, as set forth, to serve as a feed-water heater, substantially as set forth.

10. The combination, with the detachable stern-post or frame, carrying the engine, the propeller-wheel, and steering apparatus, of the adjustable clamp, as K, having a screw-threaded shank fitted to a correspondingly-threaded opening in the frame and provided with a set-screw, K², substantially as and for the purpose set forth.

11. The combination, with the engine and its operating connections, of the condenser-rudder having the tubular standard, the perforated tube E², carrying the engine-valves E, fitted within said standard and serving as the exhaust-pipe for conveying exhaust-steam to said condenser, and as a hinging-support therefor, the feed-water pipe arranged within and connected at its ends with said exhaust-tube and passing up through the valve-chamber, the pump valves I i, and means for imparting reciprocating action to said valve-tube and feed-pipe, substantially as set forth.

12. A frame or auxiliary stern-post, A, for supporting the propeller and engine, provided with a hollow or cavity, as a, for containing liquid fuel, substantially as set forth.

Witness my hand this 22d day of November, A. D. 1886.
